UNITED STATES PATENT OFFICE.

FRANK J. DOUGLASS, OF CHICAGO, ILLINOIS.

STEAM-HEATING APPARATUS.

Application filed June 18, 1925. Serial No. 37,974.

My invention relates to vacuum steam heating systems or other steam heating systems employing steam traps at the outlets of the radiators. It is the principal object 5 of my invention to provide means whereby solids of a character to float such as burnt core sand, grease, or mixtures of grease and sedimentary deposits, or other such scale or scum, shall be held back in the radiators so 10 as not to be carried, at least in any large quantities at a time, from the radiators into the steam traps, valves and boiler where it may seriously affect the proper operation of the system.

15 In a system employing a steam trap for controlling wholly or partially the entrance of the steam into the radiator by the automatic closure of the outlet valve when any appreciable amount of steam begins to escape, it is very important that the heat sensitive parts be kept clean in order that the response of the valve may be prompt and positive. Moreover, it is very important that foreign matter be kept out of the pump 20 and out of the boiler, so far as possible. Regardless of any ordinary precautions which may be taken, a radiator almost always contains a quantity of rust, scale or other foreign matter which forms a scum 25 on the surface of the water standing in the bottom of the radiator. If this matter is permitted to pass freely through the outlet bushing, it is likely to interfere materially with the proper working of the system.

30 It is accordingly the object of my invention, considered specifically, to provide an improved construction of outlet bushing which can be properly installed without difficulty by ordinary methods for taking the water through a large opening from the desired point below the surface of the water, thus preventing the entrance of the scum on the surface of the water, while at the same 35 time providing a comparatively large opening for the steam above the level of the water.

It is another object of my invention to improve devices of this type in sundry details hereinafter pointed out. The preferred 40 means by which I have accomplished my several objects are illustrated in the accompanying drawing and are hereinafter specifically described. That which I believe to be new and desire to cover by this 45 application is set forth in the claims.

In the drawing:

Fig. 1 is a side view of a radiator equipped with my improved device.

Fig. 2 is an enlarged detail, being a central vertical section through a fragmentary 60 portion of the structure adjacent to the bushing.

Fig. 3 is a vertical section taken on line 3—3 of Fig. 2.

Fig. 4 is a perspective view of my im- 65 proved bushing; and

Fig. 5 is a perspective view, similar to Fig. 4, but showing a modified form of construction.

Referring now particularly to Figs. 1 to 70 4 inclusive, 10 indicates a radiator of any approved type, the radiator illustrated being provided with a steam pipe 11 provided with a valve 12. At its opposite end, the radiator is provided with a return pipe 13, 75 equipped with a steam trap 14 of any approved type comprising a valve which is adapted to open at intervals for permitting the escape of accumulated water and to close again promptly as soon as live steam begins to escape.

The upper end of the return pipe 13 is connected to the radiator 10 by means of a bushing comprising a body 15 secured by means of screw threads in the outlet opening of the radiator, the pipe 13, in turn, being secured by means of screw threads in a longitudinally extending duct 16, which opens at the front face of the body. At the inner or rear end portion of the bushing, 80 I have provided a transversely extending duct 17 which is open at its ends both above and below the central chamber provided by the longitudinally extending duct 16 and the transversely extending duct 17. By reference particularly to Fig. 2, it will be seen that the rear wall of the transversely extending duct comprises an imperforate band extending across from side to side of the body at the level of the longitudinally extending duct, the arrangement being such that the said rear wall serves as a baffle plate with respect to the entrance of the water into and through the bushing.

In operation, with the parts in the position as shown in Fig. 2, in which position the level of the water in the radiator is controlled by the position of the lowermost part of the opening through the pipe 13, the water ordinarily will enter the chamber of 110

the bushing only at the lower end of the transversely extending duct 17 below the surface of the water, thus preventing the entrance of the foreign matter from the surface of the water in the radiator. If for any reason the water is caused to accumulate in the radiator above the level of the upper end of the vertically-extending duct 17, the scale is prevented from clogging up the opening by reason of its comparatively large size.

By the use of my construction in which two comparatively large openings are provided at opposite sides of the bushing so that the bushing can operate effectively in either of two adjusted positions, it is always possible to tighten the bushing effectively by turning it sufficiently to bring the duct 17 into vertical position. This is in contrast with a construction which can stand in only one position and which must accordingly at times be given almost a complete turn through three hundred and sixty degrees beyond the normal tightening in order to reach the required operative position.

In the construction illustrated in Fig. 5, a central chamber or recess 19 is provided, with openings 20, 21 therefrom extending longitudinally of the bushing instead of radially. The construction is, however, similar to that above described in that the rear wall of the chamber comprises a continuous imperforate baffle, extending across from side to side of the body, with openings above and below the longitudinally extending duct 16, the bushing being symmetrical with respect to the longitudinal axis so as to permit of effective use of the bushing in either of two positions adjusted 180 degrees apart.

By my invention, I have provided a construction adapted to stand in either of two adjusted positions, being arranged so that in either position a baffle is provided for maintaining a certain water level in the radiator and allowing the water to outflow from the radiator below the water level therein through a comparatively large opening while allowing the steam and air to outflow through a relatively large opening located above the water level. By this means floating solids are retained in the radiator, or at least are allowed to escape only in such small quantities as not to affect the operation of the trap, and the free passage of water of condensation, air and

steam to the trap is provided for. Sediment traps, it may be said, are entirely ineffective in this connection. Solids of a character to sink in water will be trapped and retained in any radiator of modern type. But if such heavy solids become mixed with grease or entrained by greasy matter they will float and it is the evil resulting from the entry of such matters into traps and the like that my invention has successfully overcome.

While I prefer to employ one of the constructions as illustrated in the drawing, it will be understood that I do not wish to be limited thereto, except as the same may be specifically claimed, inasmuch as it is evident that changes could well be made in the details of construction without departing from the spirit of my invention.

I claim:

1. In a steam heating system, the combination of a radiator, a steam trap, and an outlet fitting between the radiator and trap and connected with said radiator and trap comprising a member adapted to project into the radiator above the bottom of the same and having a horizontal port therethrough and at its inner end a vertical port communicating with and extending above and below the horizontal port, open at both ends and of such relatively large cross sectional area from end to end as to allow free outflow of steam and to be incapable of being clogged by solid matter in the condensate.

2. In a steam heating system, a radiator; a steam trap; and means providing an outlet port through which water of condensation, air and steam may pass to said trap, which port is located above the bottom of the radiator so that a body of water is maintained in the radiator, a water discharge port leading to said outlet port at a distance below the water level in the radiator, and an air and steam discharge port leading to said outlet port at a distance above said water level, said ports being of such relatively large cross sectional area, throughout their lengths, as to be incapable of clogging by sedimentary matter or scaling and to permit a free outflow of water of condensation, air and steam, whereby discharge of floating solid matter in the water in the radiator is checked.

FRANK J. DOUGLASS.
